UNITED STATES PATENT OFFICE.

FRANK HORNQUIST, OF MOUNT JEWETT, PENNSYLVANIA, ASSIGNOR TO THE CLIMAX
HEEL COMPANY, INCORPORATED, OF MOUNT JEWETT, PENNSYLVANIA.

TOY VEHICLE.

Application filed June 6, 1921, Serial No. 475,495. Renewed April 6, 1923.

To all whom it may concern:

Be it known that I, FRANK HORNQUIST, a citizen of the United States, residing at Mount Jewett, in the county of McKean and 5 State of Pennsylvania, have invented certain new and useful Improvements in Toy Vehicles; and I do declare the following to be a full, clear, and exact description of the invention, such as will enable others skilled 10 in the art to which it appertains to make and use the same.

This invention relates to an improved toy vehicle of the scooter type and one object 15 of the invention is to provide a toy vehicle of the class described so constructed that the child occupying the same may either sit upon the platform and propel the vehicle with his feet engaging the ground or may stand upon a step beneath and extending to 20 the rear of the platform and with one foot propel the vehicle.

Another object of the invention is to provide a toy vehicle in which the rear portion will be very strongly braced and 25 thus permit it to support the weight of the occupant in a very efficient manner.

Another object of the invention is to provide an improved type of steering post journalled in the forward end portion of the 30 platform, this post being formed in upper and lower sections which fit one within the other and are releasably held in engagement so that they may be taken apart when desired.

Another object of the invention is to so 35 construct this steering post that strain will be removed from the upper section thus permitting the vehicle to be used without danger of breakage.

Another object of the invention is to so 40 construct this vehicle that the post may be readily taken apart and thus permit the vehicle to be stored in a small amount of space.

This invention is illustrated in the accompanying drawings, wherein:

Figure 1 is a view showing the toy vehicle principally in side elevation and partially in section.

Figure 2 is a rear elevation of the improved vehicle.

Figure 3 is a sectional view taken along the line 3—3 of Fig. 1.

This vehicle is provided with a platform 45 or seat 1 having a widened rear portion.

Bracing bars 2 are secured to the under face of the platform 1 intermediate its length and extend rearwardly and downwardly in diverging relation as shown in Figs. 1 and 3 and have their rear end portions resting 60 upon and secured to a step 3 which is positioned beneath and extends to the rear of the platform. The bolster 4 is secured against the underface of the widened rear portion of the platform and has its lower 65 end portion reduced to provide abutment shoulders 5 which rest upon the bracing bars as shown in Figs. 2 and 1 and to further provide the tongue extension 6 which extends between and is secured to the inner 70 side faces of the bracing bars 2. The ground engaging wheels 7 are rotatably connected with the step 3.

The steering post is provided with an upper shaft section 8 and a lower section 75 9 having fork extensions 10 between which the forward ground engaging wheel 11 is rotatably mounted. This fork section 10 is bored from its upper end to provide a socket 12 and is provided with a reduced 80 upper end portion 13 which fits into a sleeve 14. This sleeve 14 has a reduced upper end portion which fits into an opening 15 formed in the platform and it will thus be seen that the sleeve will be provided with a shoulder 85 intermediate its length upon which the platform will rest and that the lower fork section 9 will also be provided with a shoulder against which the lower end of the sleeve 14 will rest. The upper shaft section 8 90 which carries the turning handle 16 has a reduced lower portion upon which will be mounted a collar 17 which fits into a seat 18 cut from the upper face of the platform. This collar has a reduced lower end portion 95 19 which fits into the sleeve 14 and engages the upper end of the lower fork section 9. The reduced end portion of the shaft section 8 extends down into the socket 12 and when in place a securing pin 20 is passed 100 through the lower fork section and lower end portion of the shaft thus securely but releasably holding the upper shaft and lower fork section together, and causing the fork section to be turned for 105 guiding when the upper shaft section is rotated by means of the handle 16.

When this toy vehicle is in use, the child using the same will sit upon the platform with his feet engaging the ground and by 110

pedaling with his feet can propel the vehicle forwardly or rearwardly. By turning the steering post through the medium of the handle, the vehicle can be guided in the desired direction. If desired, the child can stand upon the rear platform or step 3 and can propel the vehicle with one foot engaging the ground. It will thus be seen that the vehicle can be used either by standing 10 upon the rear step or sitting upon the platform. It will be further noted that this vehicle is so constructed that the rear portion which carries the major portion of the weight will be very strongly braced. It will 15 also be noted that the steering post is firmly braced and relieved from a great deal of strain and can be turned very easily.

I claim:

1. A steerable toy vehicle comprising a 20 platform, supporting bars secured to the under face of the platform and extending downwardly and rearwardly therefrom, a transversely extending bolster secured to the under face of the rear end portion of 25 said platform and supported upon said bars and having its lower portion extending between and secured to said bars, a step se-

cured to and extending below the rear end portions of said bars and with a surface 30 between the bars, and rotatable ground engaging supporting means for the rear portion of said vehicle.

2. A toy vehicle including a platform, and supporting means for the rear portion of the vehicle comprising supporting bars secured to the underface of the platform and extending downwardly and rearwardly therefrom in diverging relation and beyond the rear end of the platform, a transversely extending bolster secured to the underface 40 of the platform above the rearwardly extending portions of the supporting bars and having its side portions supported upon the upper edges of the supporting bars and its lower end portion extending between the 45 supporting bars, a step extending rearwardly between the bolster and the rear ends of the supporting bars and having its side portions extending beyond the side bars, and ground-engaging elements connected with the extended side portions of the step.

In testimony whereof I have hereunto set my hand.

FRANK HORNQUIST.
